CLAIM

The ornamental design for a door for entryway with refrigerator and delivery storage box, as shown and described.

DESCRIPTION

1. Door for Entryway with Refrigerator and Delivery Storage Box

1.1 : Perspective

1.2 : Back

1.3 : Front

1.4 : Left

1.5 : Right

1.6 : Top

1.7 : Bottom

1.8 : Perspective view

The broken lines illustrate environmental condition only and form no part thereof.

1 Claim, 8 Drawing Sheets
